UNITED STATES PATENT OFFICE.

MARK R. SPELMAN, OF HYDE PARK, NEW YORK.

CENTRIFUGAL SEPARATOR.

1,212,831.

Specification of Letters Patent. Patented Jan. 16, 1917.

Application filed July 30, 1915. Serial No. 42,746.

To all whom it may concern:

Be it known that I, MARK R. SPELMAN, a citizen of the United States, and a resident of Hyde Park on Hudson, in the county of 5 Dutchess and State of New York, have invented a new and Improved Centrifugal Separator, of which the following is a full, clear, and exact description.

This invention relates to centrifugal separators especially designed for separating 10 solid particles from liquid.

The general objects of the present invention are to improve the construction and operation of centrifugal separators so as to 15 be capable of a large output by being continuously in operation and entirely automatic as to the supply of the fluid to be separated and the removal of the solid particles from the basket.

20 A more specific object of the invention is the provision of a centrifugal separator in which the basket is suspended and rotated from a point above it and the liquid to be separated is supplied to the basket through 25 a pipe disposed coaxially with the basket and rotatable therein so that discharging nozzles on the pipe can deliver the material against the inner wall of the basket, the basket and pipe having relative axial movement 30 so as to distribute the material evenly on the wall of the basket.

A further object of the invention is the provision of a novel means for removing the solid material from the internal wall of the 35 basket, such means including one or more nozzles disposed externally to the basket, and directing one or more jets of fluid through the perforated wall of the basket for dislodging solid material therefrom.

40 An additional object of the invention is the employment of alternately acting valves for controlling the supply of fluid to be separated to the basket and the fluid medium for dislodging the solid material from the 45 wall of the basket, these valves being automatically operated in such relation to the vertical movement of the internal liquid supply nozzles and the external fluid jet nozzle or nozzles that the liquid supply will 50 be cut off while the fluid jets are active in dislodging the separated solid material, and the liquid supply nozzles will be active when the fluid jet nozzle or nozzles are idle.

Another purpose of the invention is to 55 so construct the basket that in sugar refinery the saccharine juices will be separated in

such a manner as to permit the usual filtering bags to be dispensed with.

With such objects in view, and others which will appear as the description proceeds, the invention comprises various novel features of construction and arrangement of parts which will be set forth with particularity in the following description and claims appended hereto.

65 In the accompanying drawings, which illustrate one embodiment of the invention and wherein similar characters of reference indicate corresponding parts in all the views, Figure 1 is a vertical section of the separator; Fig. 2 is a horizontal section on the line 2-2, Fig. 1; Fig. 3 is a detail sectional view of the basket construction; Fig. 4 is a side view of the machine; and Fig. 5 is a sectional view of the automatic valve for 70 supplying the liquid to be separated.

75 Referring to the drawing, A designates the separator, which comprises a well or casing 1 formed at its bottom with an annular collecting channel or gutter 2, and the bottom 3 of the casing is funnel-shaped and has a central duct 4 by which the solid material is conducted away from the machine. At one side of the casing the gutter 2 has a discharge opening 5 connected with a pipe 6 through which the liquid separated by the 80 machine is carried away. Attached to the top of the casing 1 is a spider 7 which has a central hub 8, and by means of this spider 85 the basket a is supported.

90 The basket a is preferably made of two shells 9 and 10 of perforated metal or equivalent reticulated material, and clamped between these two shells is a suitable fabric 11 which serves as a filtering medium. The 95 cylindrical wall of the basket is fastened to a spider 12 which has a central tubular shaft or spindle 13 which is rotatable in the hub 8 of the stationary spider 7. The basket is open at its bottom and the cylindrical wall 100 of the basket is directly over the annular ridge or curb 12 between the channel 2 and funnel 3. On the upper end of the shaft 13 is fastened a pulley or equivalent element 14 which is driven by a belt 15 or any suitable means. The pulley 14 rests on the top of the hub bearing 8 so as to rotatably support the weight of the basket a. The material to be separated is supplied through a pipe 16 which passes downwardly through 105 the shaft 13 of the basket, and the lower end of the pipe is provided with oppositely 110

disposed horizontal nozzles 17 having their outlet extremities terminating close to the wall of the basket so as to deliver the material thereon. This liquid supplying device is not only rotatable but movable axially of the basket. For this purpose the pipe 16 is slideable in the shaft 13 and it is provided with a pulley or equivalent device 18 driven by a belt or equivalent means 19. 5 This pulley 18 may be supported by a suitable bearing 20, and on the pipe 16 is a feather or equivalent means 21 whereby the pulley will rotate the pipe 16 while the latter is moving vertically. The pipe 16 moves 10 to such an extent that the material to be separated will be discharged against the internal surface of the basket throughout the vertical height of the latter. The liquid supplying device in the basket *a* moves 15 intermittently and during the idle period of the device the flow of liquid will be cut off, and during this period the solid material *m* on the internal surface of the basket will be dislodged by a jet of fluid directed from a 20 nozzle 22 disposed externally of the basket *a*. A plurality of these nozzles 22 may be employed as shown in Fig. 1, or a single nozzle may answer the purpose, as shown in Fig. 4. These nozzles are each carried by 25 the lower end of a pipe 23 slideable vertically in a guide 24 on the casing, the nozzles being adapted to move the full height of the basket so as to blow off the solid material that adheres to the internal surface of the basket, due to the centrifugal separating 30 action. The supply of fluid to the nozzles 22 is intermittent and it is cut off when the material *m* is entirely removed and the liquid supplying means in the basket again 35 begins to operate.

Any suitable means may be employed to vertically reciprocate the pipes 16 and 23, but as shown in Fig. 4, these pipes are actuated by levers 25 and 26 which are operatively connected at 27 and 28 with the pipes. The levers are intermittently oscillated by crank wheels 29 and 30 connected 40 respectively by links 31 and 32 with the levers 25 and 26. A mutilated gear 33 alternately meshes with gears 34 and 35 connected with the crank wheels 29 and 30, so that, while the lever 25 swings up and down, the lever 26 will be idle, and when the latter lever swings up and down the lever 25 will 45 be idle. The mutilated gear 33 is operatively connected in any suitable manner with a driving mechanism *D* which includes a shaft 36 on which are pulleys 37 and 38 that drive the belts 15 and 19, respectively. The 50 upper ends of the pipes 16 and 23 reciprocate in the lower ends of stationary pipes 16' and 23', there being valves 39 and 40 in the pipes 16' and 23', respectively. The valve 39, which is adapted to be opened by 55 a spring 41, has an arm 42 which is adapted

to be engaged by a collar 43 on a rod 44 that is connected with the lever 25, so that as the lever 25 swings upwardly, the valve arm 42 is raised against the tension of the spring 41 so as to close the valve, this closing movement taking place when the nozzles have reached the top of the basket. As the lever 25 swings downwardly the collar or stop 43 permits the arm 42 to swing downwardly by the spring 41 opening the 70 valve. The valve 40 is adapted to be opened by a spring as in valve 39, and it is provided with an arm 45 which is adapted to be engaged by a stop or collar 46 on a rod 47 which is connected with the pipe 23, whereby the valve 40 will be kept closed while the pipe 23 is in its lowermost position, but as soon as this pipe moves upwardly the valve 40 opens so as to permit fluid under pressure to the separator for the purpose of 85 dislodging the solid material from the basket.

By mounting the basket to rotate on a vertical shaft and by having the cleaning nozzles 22 at such points with respect to the 90 axis of the basket that the pressure due to the jets is balanced, the basket will freely rotate without lateral pressure, which will tend to bind the shaft in its bearings.

From the foregoing description taken in 95 connection with the accompanying drawings, the advantages of the construction and method of operation will be readily understood by those skilled in the art to which the invention appertains, and while I have 100 described the principle of operation, together with the apparatus which I now consider to be the best embodiment thereof, I desire to have it understood that the apparatus shown is merely illustrative and that 105 such changes may be made when desired as fall within the scope of the appended claims.

Having thus described my invention, I claim as new and desire to secure by Letters 110 Patent:

1. A centrifugal separator comprising a rotatable basket, a device disposed within the basket for supplying to the wall of the basket the material to be separated, and means for relatively axially moving the basket and the device for distributing the material over the internal surface of the basket.

2. A centrifugal separator comprising a 120 rotatable basket, a device extending into the basket from the top for supplying thereto material to be separated, means for rotating said device, and means for relatively axially moving the device and basket for distributing 125 over the internal surface of the latter the material to be separated.

3. A centrifugal separator comprising a rotatable basket, means for suspending and rotating the basket from the top, a pipe ex- 130

tending into the basket and movable axially with respect to the latter, a nozzle on the lower end of the pipe and disposed in the basket for supplying thereto material to be separated, and means for rotating the nozzle.

4. A centrifugal separator comprising a basket, a surrounding well, a support on the top of the well from which the basket is rotatably suspended, a pipe extending into the top of the basket and slidably axially thereof, and means on the lower end of the pipe for discharging against the internal surface of the wall of the basket the material to be separated.

15 5. A centrifugal separator comprising a basket rotatable on a vertical axis for separating liquid from solid material, and a plurality of means disposed outside the basket for discharging fluid through the wall of the basket to dislodge material from the internal surface thereof, said means being so spaced with respect to each other that the lateral pressures produced on the basket by the said fluid are balanced.

25 6. A centrifugal separator comprising a rotatable basket, and devices outside the basket for discharging fluid through the wall thereof for dislodging the solid material from the internal surface of the basket, said devices being so located that the pressures exerted thereby on the basket are balanced.

35 7. A centrifugal separator comprising a rotatable basket, a device outside the basket for discharging fluid through the wall thereof for dislodging the solid material from the internal surface of the basket, and means for relatively moving the device and basket for permitting the device to operate on the entire surface on which solid matter collects, said device being located normally at the bottom of the basket and operative on its upward movement to produce an undermining action on the material.

45 8. A centrifugal separator comprising a basket for separating liquid from solid matter, means for discharging the material to be separated against the inner surface of the peripheral wall of the basket, and nozzles mounted at the outside of the basket and movable parallel with the axis thereof for discharging jets of fluid through the wall of the basket to dislodge the material therefrom, said nozzles being so disposed that the lateral pressures on the basket due to the fluid striking the same will be balanced.

55 9. A centrifugal separator comprising a rotatable basket, and fluid jet discharging nozzles disposed outside of and movable parallel with the axis of the basket for dislodging solid material from the internal surface of the latter, the nozzles being so located that the pressures on the basket produced by the nozzles balance each other.

65 10. A centrifugal separator comprising a casing or wall, a basket rotatably mounted

therein, a liquid supply pipe extending into the basket from the top, nozzle means on the pipe for supplying liquid to the cylindrical wall of the basket, a pipe extending into the casing and disposed outside the basket, an inwardly directing nozzle on the lower end of the last mentioned pipe for discharging a jet of fluid through the wall of the basket, means for vertically reciprocating the pipes alternately, and automatically operated valves in the pipes.

11. A centrifugal separator comprising a rotatable basket, separate devices arranged respectively inside and outside the basket and alternately operative for supplying liquid into the basket and dislodging solid matter from the internal surface of the wall of the basket.

12. In a continuously operating centrifugal separator, the combination of a rotatable basket, means for intermittently and automatically supplying to the basket the material to be separated, and intermittently and automatically operated means outside the basket and active during the idle period of the material supply means for dislodging the separated material from the inner surface of the basket.

13. A continuously operating centrifugal separator comprising a basket, a conduit for intermittently supplying to and distributing in the basket the material to be separated, a valve intermittently opened and closed automatically for controlling the conduit, a conduit disposed outside the basket for discharging fluid through the wall thereof to dislodge the separated material, and an intermittently and automatically operated valve in the last mentioned conduit, one valve being opened while the other is closed, and vice versa.

14. A continuously operating centrifugal separator comprising a basket, a conduit for intermittently supplying to and distributing in the basket the material to be separated, a valve intermittently opened and closed automatically for controlling the conduit, a conduit disposed outside the basket for discharging fluid through the wall thereof to dislodge the separated material, an intermittently and automatically operated valve in the last mentioned conduit, one valve being opened while the other is closed, and vice versa, and means for relatively moving the basket and said conduits, the conduits being moved while the valves thereof are opened.

15. In a centrifugal separator, the combination of a continuously rotatable basket, a device movable axially of the basket for supplying and distributing the material to be separated, means adapted to be operative to move the device once back and forth in the basket and then idle to hold the device stationary, a device located outside of the

basket and movable parallel with the axis thereof to dislodge the material from the inner surface of the basket, and means adapted to be operative during the idle period of the first-mentioned means for moving the last mentioned device back and forth and adapted to be idle while the materials are being separated.

In testimony whereof I have signed my name to this specification in the presence of two subscribing witnesses.

MARK R. SPELMAN.
